CLAIM

The ornamental design for a display screen with animated graphical user interface showing circles across a line, as shown and described.

DESCRIPTION

FIG. 1 is a view of the design at a first page according to the display screen with animated graphical user interface showing circles along a line.

FIG. 2 is a view of the design transitioned from the first page to show a second page according to the display screen with animated graphical user interface showing circles along a line.

FIG. 3 is a view of the design transitioned from the first or second page to show a third page according to the display screen with animated graphical user interface showing circles along a line; and,

FIG. 4 is a view of the design transitioned from the third page to show a fourth page according to the display screen with animated graphical user interface showing circles along a line.

The appearance of the transitional image sequentially transitions between the images shown in FIGS. 1, 2, 3, and 4. The process or period in which one image transitions to another image forms no part of the claimed design.

The outermost dashed broken line depicts a display screen that forms no part of the claimed design. The remaining broken lines, including all text shown within the graphical user interface, illustrate portions of the graphical user interface that form no part of the claimed design.
